UNITED STATES PATENT OFFICE

166,430

DINNER PLATE OR SIMILAR ARTICLE

Franz Wagner, Chicago, Ill.

Application October 30, 1951, Serial No. 17,174

Term of patent 7 years

(Cl. D44—15)

To all whom it may concern:

Be it known that I, Franz Wagner, a citizen of the United States, residing at Chicago, county of Cook, and State of Illinois, have invented a new, original, and ornamental Design for a Dinner Plate or Similar Article, of which the following is a specification, reference being had to the accompanying drawing, forming a part hereof.

The sole figure is a top plan view of a dinner plate or similar article showing my new design. The dominant feature resides in the surface ornamentation on the flange and dished-out portion of the plate or similar article as shown.

I claim:

The ornamental design for a dinner plate or similar article, as shown and described.

FRANZ WAGNER.
